FIRE CHECK

Hartwig Millard Hanson, Baltimore, Md., assignor to The C. M. Kemp Manufacturing Company, Baltimore, Md., a corporation of Maryland

Application October 15, 1953, Serial No. 386,322

7 Claims. (Cl. 137—75)

The present invention relates to an improvement in fire checks which are adapted to be installed in pipe lines used to convey mixtures of gases or gas and air from a point of mixing or generation to a point of consumption or burning.

One of the objects of the present invention is to provide a fire check having a self-closing valve, in which all of the linkage for opening and closing the valve and for resetting the check is wholly enclosed within the casing and all of the check setting and testing levers are located on the outside of the casing.

Another object of the invention is to simplify the linkage required for the operation of the check.

Another object of the invention is to provide a fuse holding means which is separately mounted on the casing and which may be easily and quickly removed for replacing a melted fuse.

A further object of the invention is to provide a signal associated with one of the outside levers connected with the valve closing mechanism for indicating the position of the valve and the condition of the check setting.

With these and other objects in view, the general principle of the invention is illustrated in the accompanying drawings and described in the detailed description that follows together with the manner in which the improved fire check is constructed including its uses and advantages.

In the drawings:

Figure 1 is a top plan view of the fire check showing the control arms.

Figure 2 is a sectional view of the same, taken along line 2—2 of Figure 1.

Figure 3 is a top plan view similar to that shown in Figure 1, taken along the line 3—3 of Figure 2.

Figure 4 is a fragmentary view partly in elevation and partly in section, showing the fluid control valve in closed position, with its opening lever.

Figure 5 is a sectional view similar to Figure 4 showing the fluid control valve in open position.

Figure 6 is an enlarged fragmentary view partly in section of the signal means on line 6—6 of Figure 1, showing the signal in normal non-signaling position.

Figure 7 is a similar view of the signal means released to its signaling position.

Figures 8 and 9 are top plan views of the fuse, or fusible link member.

Figure 10 is an inverted plan view of the mounting for the fusible link.

Figure 11 is a fragmentary view looking upwardly from the line 11—11 of Figure 2 showing the attachment of the fusible link to the mounting.

Referring now to the drawings, the fire check comprises a casing 1 having an inlet opening 2 and an outlet opening 3. The casing is subdivided into three general compartments, one adjacent each of the openings and a central compartment lying between the two end compartments. Adjacent the inlet opening there is provided a self-closing valve 4 and a compression spring 5 for urging the valve toward the valve seat 6, which in turn

2

is located within the compartment wall 7 separating the compartment adjacent the intake opening and the central compartment. The valve is carried upon a valve stem 8, one end of which is slidably receivable within a bore 9, located within a cap 10. The cap 10 is threaded into an opening in the casing opposite the valve seat. The opposite end of the valve stem 8 extends through and below the opening of the valve seat and is provided with a bearing surface on its inner end. Positioned at right angles and to one side of the longitudinal axis of the valve stem 8 is a rotatable shaft 11 extending from a point within the casing outwardly through a bearing in one side of the casing. The inner end of the shaft terminates at a point adjacent the inner end of the valve stem. About the shaft portion extending through the housing and cover 12 is a packing 13 and a packing nut 14 for preventing the escape of the gas mixture from the casing. On the outer end of the shaft 11 is a lever 15 keyed thereto and secured by a set screw 16. On the inner end of the shaft 11 is an arm having a shoe 17, which is keyed thereto and secured by the set screw 18, the same as lever 15 at the other end of shaft 11. The shoe is positioned to contact the inner face of the valve stem 8 for the purpose of moving the valve stem outwardly through the bore 9 to unseat the valve 4, and against the pressure of the compression spring 5 by moving the lever 15 in the direction of the arrow 19 shown in Figure 1. When the lever is moved in the opposite direction the shoe 17 is in the position as shown in Figure 4, the valve being forced into the seat by the compression spring 5 to close the valve. Therefore, the fluid control valve 4 may be manually opened by the lever 15 located on the outside of the casing, to set it, and to ascertain that it is properly working. Also fixedly secured by set screw 20 to the shaft 11 is an arm 21, which is provided with a yoke 22 which when connected with a fuse or fusible link 23, is adapted to hold the shaft 11 in a predetermined position in which the shoe 17 by pressure on stem 8 compresses the spring 5 and holds the valve 4 open in the position shown in Figure 5.

Also extending outwardly through the casing is a shaft 24, which is rotatably supported within a bearing 25 in the small cover member 26 on larger cover 12, the shaft 24 being parallel with the shaft 11.

As stated hereinbefore, the casing is divided into three compartments, one connecting with the inlet opening 2 of the casing and one connected with the outlet opening 3, while the third compartment is located centrally between the two. The compartment connected with the inlet opening in which the valve 4 is located is separated from the central compartment by the wall 7. The compartment connected with the outlet opening 3 is separated from the central compartment by the wall 27. The wall 27 has located therein a relatively large threaded opening and within the opening there is provided a flame interrupting screen 28. This flame interrupting screen 28 consists primarily of one or more closely held perforated plates and extends throughout the only opening within the wall 27 between the two compartments.

Referring again to the shaft 24, there is provided an enlarged head member 29 fast thereto having a recessed portion 30 and a central threaded opening 31, see Figure 10, for receiving a stud 32 for clamping the fuse or fusible member 23, into the proper location to engage the yoke 22 when the arm 21 is moved to a position in which the valve is opened.

The shaft 24 is also provided with packing and a packing nut 33 in small cover member 26 to prevent the escape of gas about the shaft.

Fixedly secured to the outer end of the shaft 24 is a lever 34 by which the shaft may be rotated through a predetermined arc. The small cover member 26 in which

the shaft 24 is mounted is held to the casing cover 12 by the studs 35 and the large cover 12 is held to the casing by studs 36.

As mentioned hereinbefore the fusible member is carried by the head 29 located on the inner end of the shaft 24. The construction of the fusible member 23 is illustrated best in Figures 8 and 9. This fuse 23 is made up of mating members 37 and 38 which are fastened together by solder, or other suitable fusible materials 39, along the contacting edges of the mating sections of the members. This fusible material will be of sufficient strength to normally keep the spring 5 in compressed position and the valve open, but in the presence of a flame it will melt, releasing the spring which will act to close the valve.

When the fuse member 23 is secured to the head 29 it rests on the recessed surface 30 and will swing with the rotation of the shaft 24. The fusible member 23 has a pin 40 in its swinging end to engage yoke 22.

There is provided on the small cover 26 and adjacent extension 41 of the lever 34 a pair of spaced stops 42 and 43. The shoe 17 is of such length and so placed upon the shaft 11 that when the lever 15 is pressed to its limit in the direction of the arrow 19 that the valve will be opened. During the movement of the lever 15 to open the valve, the extension 41 of the lever 34 must be in contact with the stop 43, to remove the fusible member from the arc of rotation of the yoke 22. However, after the lever 15 has been moved to its full extent, the arm 34 is moved to nearly contact the extension with stop 42 at which position the pin 40 carried by the fuse member 23 will be engaged by the yoke 22 at the swinging end of the arm 21, and prevent the shaft 11 from rotating and closing the valve. The lever 15 is held firmly, to hold the valve open, until the fusible member 23 and its pin 40 are in proper position, then the lever 15 is slowly released and the yoke 22 engages the pin 40. In this position the extension 41 is nearly against stop 42.

Extending outwardly from the side of lever arm 15 is a U-shaped bracket 44 having a pin 45 extending through the outer fork thereof. Pivotably supported upon the pin 45 is a flat disk-like signaling member 46, preferably painted in a bright color, such as red. As long as the lever 15 is held in the position shown in Figure 1, the signal member 46 is in a downward position as shown in Figures 1 and 6, but if the lever 15 is moved in the opposite direction as shown in Figure 7, by the action of the spring 5 in the closing of the valve, the signal will be elevated by a pin 49 projecting on the cover 12, which is adapted to contact the angular portion 48 of the signal member 46, which is positioned below the pivot pin 45. The portion 47 of the signaling disk is of substantially the same form as the portion 48 and is for positively lowering the signaling disk when the lever has been moved to open the supply valve 4 by contacting the pin 49 from the opposite side. The disk levers 47 and 48 project from the disk like the legs of an inverted V.

In order that the flame interrupting means may be easily replaced, there is provided an opening into which a plug, or cap 50 is fitted.

In operation, the device is first placed in a line carrying an inflammable gas mixture flowing in the direction of the arrows in Figure 1. The valve being open as shown in Figure 5 and being held in that position by the fusible link 23, the gas mixture will flow into the compartment adjacent the intake opening 2, through the valve opening into the central or intermediate chamber, up through the flame interrupting means 28, into the compartment adjacent the outlet 3 and out into the line. As long as the temperature of the gas is not above a certain point the fusible link will remain whole and hold the valve open against the force of the spring 5. However, if there is a back fire in the line leading from the outlet 3, sometimes referred to as a "flash back," the flame will enter

the outlet passage and pass into the compartment adjacent thereto, in which the fusible link 23 is located. The composition 39 is melted and the link 23 separates, which releases the shaft 11. By the action of the spring 5, the valve is instantly closed and through the rotation of shaft 11 the handle 15 is moved toward the pin 49, whereupon the lever 48 contacts the pin 49 and lifts the disk 46 to extend it upwardly as shown in Figure 7. This signal indicates that the fuse has melted and the gas mixture has been cut-off in the line and at the same time the burning gas mixture will be stopped by the flame interrupting means 28, as the flame tends to enter the central compartment. After the lines have been cleared a new fuse element must be inserted to again hold the valve in open position.

In replacing the fuse element, the small cover 26 in which the shaft 24 is carried is removed by taking out the studs 35 which also removes one end of the burned out fuse, a new fuse is secured to the head member 29 and the other end of the fuse is removed from the compartment, after which the cover 26 is replaced. When the cover is being replaced the extension 41 of lever 34 is turned to contact stop 43, after which the valve is reset in open position as previously described.

While a particular structure showing the invention has been illustrated and described, it is not intended as a limitation, the invention being defined by the claims.

What is claimed as new and is desired to be secured by Letters Patent is:

1. In a fire check for combustible fuel pipe lines, the combination of a casing having inlet and outlet passages, a self-closing valve within the casing between said passages, a first shaft within the casing extending to the outside thereof and a lever on the outside end thereof, a lever on said shaft within the casing having one arm connected with the valve, a fuse link lever on said shaft within the casing, a second shaft within the casing extending to the outside thereof, a fuse link within the casing connected to and rotating with said second shaft, and means on the outside end of the second shaft to rotate the same, said fuse link at its swinging end upon relative rotation of said shafts, interlocking with said fuse link lever to hold said valve open.

2. The fire check of claim 1 including a stop on the outside of the casing to indicate the inner position of the fuse link swing.

3. In a device as claimed in claim 1 in which the outside lever carried on the first mentioned shaft is provided with a flat disk member pivoted to the lever and adapted to lie parallel with the casing when the lever is in position to open the valve and means on the disk and casing to raise the disk perpendicular to the casing when the lever is in position to close the valve.

4. In a device as claimed in claim 1 in which the fuse link supporting shaft is mounted on a detachable cover member, whereby the fuse link supporting and rotating mechanism may separately be removed from the casing without disturbing the remaining elements of the fire check.

5. A fire check for combustible fuel lines comprising in combination, a casing having inlet and outlet passages, a self-closing valve in the inlet passage including a compression spring within the casing to close the valve, operating means to open the valve, including a rotatable shaft extending from a point within the casing outwardly through one side of the casing, a lever fixedly secured to the outer end of the shaft to rotate the same, and means connected to the inner end of the shaft to open the valve as the shaft is rotated, a fuse link engaging lever on the shaft, a fuse link, a support shaft in the outlet compartment having means on the inner end thereof to fixedly support the fuse link at one end, the shaft extending outwardly through the casing and being rotatable to manually connect the fuse link other end to the fuse link en-

75

gaging lever to normally hold the valve in open position against the pressure of the compression spring.

6. A fire check for combustible fuel lines having in combination, a casing having inlet and outlet passages, a self-closing valve including a guiding stem and a compression spring for urging the valve to a closed position within the casing between the openings, a valve operating shaft having its axis perpendicular to the valve stem and parallel with the face of the valve, the shaft extending from a point within the casing outwardly through one side thereof, a lever fixedly secured to the portion of the shaft extending outside the casing, an arm fixedly secured to the inner end of the shaft, the arm having a shoe thereon adapted to apply pressure to the valve stem for urging the valve to an open position upon rotation of the shaft by the lever, a fuse link, a fuse link engaging lever fixedly secured on said shaft and located within the casing and between the outer lever and the arm adapted to engage with one end of said fuse link for holding the shaft in position to maintain the valve open, means for rotatably supporting the fuse link comprising a second shaft extending from a point within the casing to a point without the casing and parallel with the first named shaft and having a lever on the outer end portion thereof, a holding and clamping mechanism on the inner end of the fuse link

5

10

15

20

25

supporting shaft for receiving and holding one end of said fuse link, the fuse link being movable by its shaft and outer lever to engagement with the fuse engaging lever carried by the first named shaft when the said first named shaft is in position to open the valve.

7. In a fire check for combustible fuel pipe lines, the combination of a casing having inlet and outlet passages, a self-closing valve within the casing between the passages, a rocker shaft in the casing extending to the outside thereof, said shaft having one lever connected with said valve within the casing to maintain the valve open, and another lever extending therefrom within the casing, a fuse link, means within the casing to support the link to engage the last named lever to hold the valve open, pivoting means connected with said rocker shaft without said casing to lie in one position when the valve is open and means on the casing cooperating with said pivoting means to swing the same to another position when the valve is closed.
